(57) CLAIM

The ornamental design for a compact hairband holder as shown and described.

DESCRIPTION

FIG. 1 is a perspective view of the compact hairband holder of this invention;

FIG. 2 is a left end elevation view of that which is shown in FIG. 1;

FIG. 3 is a right end elevation view of that which is shown in FIG. 1;

FIG. 4 is a top plan view of that which is shown in FIG. 1;

FIG. 5 is a front elevation view of that which is shown in FIG. 1, the rear elevation view being a mirror image; and, FIG. 6 is a bottom plan view of that which is shown in FIG. 1, shown in use holding hairbands.

The broken lines in the drawings represent unclaimed environmental subject matter and form no part of the claim.
